Des. 182,482
Patented Apr. 8, 1958

182,482

DOUBLE SINK

Cyrus Schwartz, Los Angeles, Calif.

Application May 31, 1957, Serial No. 46,433

Term of patent 14 years

(Cl. D4—2)

Fig. 1 is a top plan view of a double sink, showing my new design;

Fig. 2 is a bottom plan view thereof;

Fig. 3 is an elevation of one side of the double sink, the opposite side having the same appearance, and,

Fig. 4 is an elevation of one end of the double sink, the opposite end having the same appearance.

I claim:

The ornamental design for a double sink, substantially as shown and described.
